UNITED STATES PATENT OFFICE.

JAMES SHARPLES, OF BIRMINGHAM, ENGLAND.

BURNER FOR OIL-LAMPS.

SPECIFICATION forming part of Letters Patent No. 662,826, dated November 27, 1900.

Application filed May 23, 1900. Serial No. 17,721. (No model.)

To all whom it may concern:

Be it known that I, JAMES SHARPLES, a subject of Her Majesty the Queen of Great Britain and Ireland, residing at 699 Coventry road, 5 in the city of Birmingham, in the county of Warwick, England, have invented certain new and useful Improvements in and Connected with Burners for Oil-Lamps, of which the following is a specification.

10 This invention consists of the herein-described improvements in and connected with burners for oil-lamps, so as to facilitate extinguishing the lamp.

15 My invention is applicable to oil-lamp burners of all kinds, whether they are what is known as "single-wick" burners—that is, fitted with only one wick-tube—or whether they are burners provided with what are known as "duplex" or "circular" or "crescent" or "central-draft," or of other kind of wick-tubes.

20 I will describe my invention by referring to the accompanying drawings, on which—

Figure 1 is a sectional front elevation of an ordinary flat-flame single-wick lamp with my invention applied thereto. Fig. 2 is a sectional side elevation of the same. Fig. 3 is a sectional plan of the burner and gallery part of the same. Fig. 4 is a sectional elevation 25 of what is known as a "duplex" flat-wick lamp-burner and gallery with my invention applied, and Fig. 5 is a sectional plan of the same.

The same letters of reference indicate the 30 same or corresponding parts in all the figures.

I will first describe the arrangement of my invention illustrated by Figs. 1, 2, and 3.

In carrying out my invention I provide an air-inlet hole or pipe A in the gallery B of the 35 burner immediately above the base C, which screws into the hole in the reservoir D, this air-inlet pipe or hole being closed by a suitable plug or valve E. Within the gallery B and surrounding the wick-tube F, I provide 40 a metallic or other non-combustible funnel G, the lower end g' of which is fixed to and closed by the diaphragm C', below which the wick-spindle H is located. The top g² of this 45 funnel is open and is somewhere about level 50 with or slightly above the top of the wick-tube F and is rather larger than the wick-tube, (see Fig. 3,) so as to leave a narrow space all around between the outside of the wick-tube F and the inside of the top g² of

the funnel G. The funnel G thus forms an 55 air-chamber, the only openings to which are the inlet hole or pipe A, which is connected thereto, and the outlet g² at the top around the wick-tube F.

When the lamp is burning and the air-inlet hole or pipe A is closed, the air contained in the air-chamber formed by the funnel G expands through the heat and is therefore at a lower pressure than the external atmosphere.

60 To extinguish the light, it is only necessary to open the air-inlet hole or pipe A by removing the plug or valve E, so that the inrush of cold air through the pipe A into the chamber in the interior of the funnel G and out through 65 the top against the flame will instantly extinguish the same.

70 The sides g⁵ of the funnel are inclined toward the top, so as the better to direct the inrush of air against the flame.

75 When my invention is applied to a circular or annular or crescent-shaped burner, the shape of the top of the funnel G is made to correspond therewith, so as to direct the inrush of air against the flame to extinguish the 80 same when the air-plug or air-inlet valve is opened, as above described.

In the case of a duplex burner the top of the funnel G is of course made with two outlets g² g³, (see Fig. 4,) corresponding with the 85 two wick-tubes F' F².

90 What I claim as my invention, and desire to secure by Letters Patent, is—

1. A burner comprising a wick-tube, an im- 95 perforated funnel surrounding the same hav- 90 ing its lower end closed about said wick-tube, a wick-spindle located entirely outside of said funnel, a passage leading to the lower part of said funnel said passage being adapted to be closed to the outside atmosphere.

2. A burner comprising a wick-tube, a funnel surrounding the same, a diaphragm clos- 100 ing the lower end of said funnel, a spindle located below said diaphragm, a passage leading from the lower part of the funnel and a removable stopper closing the end of said passage.

In witness whereof I have hereunto set my hand in presence of two witnesses.

JAMES SHARPLES.

Witnesses:

CHARLES BOSWORTH KETLEY,
HERBERT WHITEHOUSE.
